UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

MINING MACHINE.

Application filed June 5, 1922. Serial No. 566,154.

This invention relates to improvements in kerf cutting mining machines particularly adapted for use in the room and pillar system of mining, although also adapted for use in other systems of mining, as for instance the longwall or panel systems.

The principal object of this invention is to provide a new and improved machine of the character described having power actuated traction devices capable of propelling the machine along the ground, both for moving from place to place in the mine and for guiding and controlling the machine along the working face to cut a continuous kerf.

In carrying out my invention, I utilize as the principal features of my machine, a body portion provided with a swivelled cutting element and a plurality of power actuated traction devices adapted to support and propel the machine and cutting element. The cutting element comprises a cutter bar which is swivelled centrally of the machine, and is adapted to be automatically swung in a substantially horizontal plane into various positions with respect to said body portion. The traction devices are arranged so that one or more may be raised to permit the cutter bar to move thereunder and thereafter may be returned into supporting engagement with the ground under certain conditions as will hereinafter appear. Auxiliary supporting means for the body portion are also provided to afford stability to the machine when one or more of the traction devices is out of supporting engagement with the ground. Means are also provided when desirable whereby a flexible draft rope or its equivalent may be used to assist in feeding the machine to the coal.

The invention may best be understood by reference to the accompanying drawings in which

Figure 1 is a plan view of a machine embodying the various features of my invention.

Fig. 2 is a view in side elevation of the machine shown in Fig. 1 with portions thereof broken away to show details of the operating mechanism.

Fig. 3 is an end view of the machine looking from the right of Figs. 1 and 2, with a portion of the mechanism for swivelling the cutter bar shown in section.

Fig. 4 is a longitudinal cross-section of the machine taken on line 4—4 of Fig. 1. 55

Fig. 5 is a detail in horizontal cross-section taken on line 5—5 of Fig. 3.

Fig. 6 is a transverse cross-section taken on line 7—7 of Fig. 2 drawn to a somewhat larger scale than the preceding figures. 60

Fig. 7 is a transverse cross-section taken on line 8—8 of Fig. 2 shown in the same scale as Fig. 5.

Fig. 8 is a detail in perspective showing the elevating mechanism for the traction devices at one side of the machine. 65

Figs. 9, 10 and 11 are details showing parts of the power transmission gearing.

Figs. 12, 13, 14, 15 and 16 are diagrammatic views showing the machine in various 70 positions during the cutting operation.

Fig. 17 is a diagrammatic view showing the application of supplemental draft means to the machine.

Referring now to details of the embodiment illustrated in the drawings, 10 indicates a main frame on which is mounted a motor casing 11 enclosing a suitable prime mover such as an electric motor. The machine is supported on a plurality of traction devices, preferably comprising rotatable wheels 12, 12 with traction studs of any suitable form thereon. In the form shown, said wheels are four in number and positioned at the corners of the machine. 13 indicates a cutter arm which is provided with an endless cutter chain 13^a of the usual construction. In the form of my invention illustrated, this cutter arm is pivotally mounted under the central portion of the main frame 10 and arranged to cut a kerf near the mine floor. The inner end of said cutter arm is supported on a suitable bracket 14, which depends from a horizontally disposed turntable 15 rotatably mounted on an annular portion 10^a forming a part of the main frame 10 and retained thereon by a bearing ring 15^a, as shown in Fig. 6. Details of the mechanism for operating this turntable will hereinafter appear. 95

An auxiliary supporting device preferably comprising a pan 16 is mounted underneath and spaced from the turntable 15 and rigidly connected therewith by suitable supports 17, 17. This pan preferably extends laterally under the inner end of the cutter 100

arm as shown in Fig. 4. Under certain conditions, it is adapted to rest in sliding and supporting engagement with the ground. The lateral margins 18, 18, of the pan 16 are preferably turned upwardly, as shown, so that the pan may readily move over uneven floor. The pan is open on all sides, however, so as to permit the cuttings carried rearwardly by the cutter chain 13^a to be readily discharged therefrom.

In order to allow the cutter arm to be swung from a position in which it extends from one end of the machine as shown in Fig. 12 to a position in which it extends 15 from the side of the machine such as in Fig. 15, I provide means for temporarily raising the wheels 12, 12, so as to allow the cutter arm to pass thereunder, and thereafter said wheels may be lowered again into engagement 20 with the ground. In the form of machine illustrated, I have elected to show one in which the cutter arm may be swung on all sides of the machine, and to this end all four of the wheels 12, 12, are provided with 25 means actuated by the motor whereby they may be raised and lowered. The arrangement is such that each wheel may be actuated independently of the other wheels.

The mechanism for raising and lowering 30 the wheels with respect to the frame will now be described in detail. Referring first to the wheel which appears adjacent the motor casing 11 in Fig. 2, it will be seen that this wheel has its axle 20 journaled at the 35 outer end in an arm 21 and at the inner end in an arm 22 (see Fig. 8). These arms are pivotally mounted on a transverse shaft 23 mounted at the side of the main frame. A pair of upright actuating arms 24, 24, are 40 connected to the pivoted end of the arm 21. In the preferred form, arms 24, 24, are integral with arm 21 as shown and form therewith in effect a bell crank lever by which the wheel may be pivotally swung about the 45 shaft 23 to be raised and lowered as indicated in dotted lines in Fig. 2. The upper end of the arms 24, 24, are actuated by mechanism driven by the motor, which in the embodiment illustrated comprises a longitudinally disposed screw member 25 having one end in threaded engagement with a worm gear 26 and having its opposite end enlarged as indicated at 27, and extending into a horizontally disposed guide block 28 50 carried on the frame. A pair of pivoted links 29, 29, connect end portion 27 of screw 25 and the ends of the arms 24, 24. The worm gear 26 is mounted on a support 30 and is meshed with a worm 31 mounted on a transverse shaft 32. This worm 31 has operative connection with the motor through the following gear train which will now be traced beginning with the motor 11. Referring to Fig. 4, it will be seen that the motor 55 driving pinion 35 drives a gear 36 on a shaft

37 which extends centrally and longitudinally to one end of the machine. A worm 38 on this shaft drives a worm gear 39 carried on a shaft 40 arranged above and at right angles to the shaft 37. The driving mechanism on the two sides of the machine being similar, as before set forth, the same mechanisms indicated will be duplicated on opposite sides of the machine. A reversing clutch 41 of a usual type is feathered on the shaft 40 between a pair of oppositely disposed mitre gears 42, 42, both of which are meshed with a mitre gear 43. This clutch may be thrown into engagement with one or the other of the mitre gears 42, 42, so that the 75 gear 43 may be driven in either direction, as desired. The gear 43 is connected with a variable speed transmission device 44. This transmission device preferably comprises a friction controlled mechanism capable of transmitting power through a wide range of speeds. Details of this transmission device (of which there are two of similar construction) are shown in Figs. 9, 10 and 11. The driving member of each of 80 these devices is the shaft 45 carrying the mitre gear 43 just mentioned. A sun gear 46 is keyed on the shaft 45 and is meshed with a planetary gear pinion 47 rotatably mounted in a cage 48. There may be a plurality of such planetary gear pinions, as desired. The cage 48 comprises a pair of oppositely disposed plate members 48^a and 48^b connected by a bolt 48^c or the like and rotatably mounted on the shaft on opposite 90 sides of the sun gear as shown in Fig. 9. The outer periphery of planetary pinion 47 is meshed with an internal gear carried by a casing 49 mounted free to rotate with respect to the other portions of the transmission device. Adjacent the planetary pinion 47 and unitary therewith is a planetary pinion 50 of a lesser pitch diameter. This planetary pinion 50 is meshed with an internal gear carried by a driven member 51. A gear member 52 is mounted to rotate with driven member 51. A friction band 53 of any suitable construction is mounted on the casing 49 and is provided with a handle 53^a, by which the rotation of said casing 49 may 100 be controlled under certain conditions as will hereinafter more fully appear. Means is also provided for locking the cage 48 against rotation which comprises a longitudinally movable gear segment 54 adapted to engage a toothed periphery 55 formed integral with the outer plate 48^a of said cage. In Figs. 10 and 11 it will be seen that each of the two planetary transmission devices are provided with locking devices 54, 54, supported on the frame and movable independently of each other by means of suitable shifting levers 54^a, 54^b, or the like. 110

The operation of this planetary transmission is as follows: When it is desired to drive 115

at low speed, the locking member 54 is thrown out of engagement with the geared periphery 55 of the cage 48 so as to allow said cage to rotate freely. Friction band 53 on the casing 49 is tightened so as to restrain said casing from rotation. The planetary gears will, when driven by the sun gear, rotate about the axis of the latter. The planetary gear 50, which rotates on its own axis with the gear 47, is meshed with the internal gear member 51, but being of less pitch diameter than the gear 47, the internal gear member 51 and driven gear 52 are rotated at a greatly reduced speed. This reduction in speed depends upon the difference in pitch diameters of the planetary gears 47 and 50. Variation in driving speeds may be obtained by loosening the friction band 53 so as to allow the casing 49, which is under a constant torque caused by the pinion 47 meshed therewith, to rotate slowly in the opposite direction. This will cause a proportionate reduction in the effective driving speed transmitted to the driven gear 52. If the friction band 53 is entirely released, the casing 49 will rotate freely and no driving torque will be transmitted to the gear 52.

When it is desired to drive at high speed, the locking member 54 is engaged with the toothed periphery 55 of cage 48 so as to restrain said cage from rotation. The friction band 53 is released and the sun gear 46 then drives the gear 52 through the medium of planetary gear members 47 and 50 and internal gear member 51. Through this driving connection there is a slight gear reduction in driving speed, but not nearly as great as the reduction caused at low speed in which the cage 48 is free to rotate as has been above described.

From the above description it will be seen that each of the planetary devices 44, 44, provides variable speed transmission to the driven members 52, 52. At low speed the cage 48 carrying the planetary gears is free to rotate, and a wide variation in effective driving speeds varying from zero to the maximum of the low speed gearing may be provided by varying the tension on the brake band 53 which controls the rotation of the casing 49. At high speed the cage 48 is locked against rotation and there is a relatively slight reduction in the driving speed between driving member 45 and the driving gear 52.

The driven gear 52 is meshed with a gear 56 keyed on a longitudinally disposed shaft 57. A bevel gear 58 on said shaft is meshed with a bevel gear 59 on a transverse jack shaft 60 (see Fig. 7 and Fig. 9). A gear 61 is mounted to rotate with bevel gear 59 and drives the gear 62 on the transverse shaft 32 which carries the worm 31 associated with worm 26 of the elevating mechanism heretofore described. A sliding clutch

64 is feathered on said shaft and is adapted to throw the elevating mechanism into and out of engagement with the motor. From the foregoing description it will be seen that the wheels may be raised or lowered at will by engaging clutch 64 with worm 31 and setting the reversing clutch 41 to drive in the direction desired. The clutch 21 will manifestly be moved at a slow speed, as it is actuated through the several gear reductions described.

Mechanism of similar nature is provided for raising and lowering the other wheel of the pair at one side of the machine. The bell crank lever 69 connecting the second wheel with the frame is provided with an upper arm 70 which, in the present construction, is curved in order to avoid interference with the shaft 32, as shown in Figs. 2 and 8. This arm is actuated by a screw member 71 threaded at one end in a worm gear 72 and supported at the other end in a guide block 73. The screw member is connected to the arm 70 by a single pivoted link 74. The worm gear 72 is actuated by a worm 75 through clutch 76 on the shaft 32.

The mechanism for controlling and driving the traction wheels 12, 12, also has operative connection with the motor 11. Each pair of wheels at one side of the machine is preferably driven and controlled as a unit, and in the form shown, these units are similar, so that a description of the mechanism at one side will serve to show the construction and operation of both of said units.

From the foregoing description it will appear that gear 59 on transverse shaft 60 is adapted to be reversibly actuated at various speeds through the transmission device 44. A drive gear 80 is also mounted on shaft 60 and has a toothed periphery 81 adapted to engage a rack 82 arranged about the periphery of one of the wheels 12. The gear 80 is further meshed with an idler or reach gear 83 on shaft 83^a which in turn is meshed with a gear 84 mounted on the shaft 23. The gear 84 is meshed with the rack 85 formed on the periphery of the opposite wheel 12 at the motor end of the casing. The driving gears 80 and 84 are thus driven in unison, and in the same direction. Said driving gears are also mounted concentric with their respective wheel supporting arms 69 and 21, so that they are in driving engagement with their respective wheels in all positions of the latter.

Driving gears 80 and 84 may be thrown into and out of operative connection with the motor by means of a shifting clutch 86 feathered on the hub portion 87 of the driving gear 59.

A brake for controlling each of the driving units is provided which comprises a drum 88 keyed on idler gear 83 and having a friction band 89 actuated by any suitable

means such as two oppositely acting worm devices 89^a, 89^b, associated with an operating handle 89^b, adapted to extend laterally from the side of the machine in position to be readily controlled by the operator.

The mechanism for actuating the cutter chain is shown in Figs. 1 and 6. A bevel pinion 90 is carried on the shaft 37, which has already been described as being operatively connected to the motor 11 through the gear 36 and armature pinion 35. The bevel pinion 90 is meshed with a horizontally disposed bevel gear 91 mounted on a vertical shaft 92 extending concentrically through the turntable 15 which supports the cutter arm. A clutch ring 93 is mounted on said shaft and is adapted to be engaged by a plurality of clutch members 94, 94, carried by a vertically movable clutch sleeve 95 and adapted to extend through apertures 96, 96, in the gear member 91 to engage the clutch jaws 97, 97, carried by said clutch ring 93. A chain driving sprocket 100 is mounted at the lower end of the shaft 92, and is adapted to drive the cutter chain supported on the cutter bar. By means of the arrangement just described, the cutter chain may be connected to the motor or disconnected therefrom by means of the clutch 95 and may be driven in either direction, if desired, by reversing the direction of rotation of the motor in the usual manner.

The mechanism for swinging the turntable and cutter arm carried thereby comprises a gear 110 (see Figure 2) rotatably mounted at the outer end of the shaft 37 and adapted to be clutched to said shaft by suitable means such as a cone clutch 111. A gear 112 on the end of a longitudinally disposed shaft 113 is driven by gear 110 through an idler gear 114. The shaft 113 extends forwardly underneath the motor casting 11 and has a worm 115 thereon which engages a worm gear 116 mounted to rotate on a vertical axis. This worm and worm gear is preferably of the "self-locking" type, that is to say, the pitch of worm 115 is such that the associated mechanism for driving the turntable 15 is locked against rotation unless positively driven by the motor. By means of this arrangement, the turntable and cutter arm carried thereby may be locked in any desired position, as for instance, when the cutter arm is extending laterally from the frame in position to make a cut along the working face as shown in Fig. 15.

In order that the turntable may be rotated at a relatively slow speed suitable for feeding the cutter arm to the coal, gear reduction mechanism is provided, as for instance, a planetary transmission device, details of which are shown in Figs. 3, 4 and 5. A casing 117 is integral with the main frame 10 and has a centrally disposed stud 118 in which is journaled a shaft 119. The driving

worm gear 116 has an upwardly extending hub portion 120 journaled about this stud and provided at its upper end with a pinion 121 which forms the sun gear of the planetary. A plurality of planetary gears 122, 70 122, are rotatably mounted on studs 123, 123, carried by a plate 124 fixed to the casing 117. These planetary gears are meshed at their inner peripheries with the sun gear 121 and at their outer peripheries with the internal 75 gear 125 carried by a gear member 126 which is keyed to the upper end of shaft 119. A cover 127 is provided to enclose the top of the casing 117 and provide bearing for the upper end of shaft 119 and gear member 126. 80 A driving pinion 130 is carried at the end of the shaft 119 which extends through the casing 117, said pinion being meshed with the toothed periphery 131 of the turntable 15. 85

By means of the planetary mechanism just described, the turntable 15, may be rotated by power to swing the cutter arm into any desired angular position and to feed the cutter arm to the coal. 90

Under certain working conditions, as for instance when the cutting is hard and the mine floor is of such a nature that sufficient traction is not afforded to the traction wheels, means supplemental to the traction devices may be provided for feeding or controlling the machine, comprising a draft rope 140, indicated in dotted lines in Fig. 1 and in full lines in Fig. 17. This draft rope may be detachably connected to the periphery of the wheel by any suitable means, such as a hook 141 at one end of the rope having engagement in a suitable aperture 142 formed in the periphery of the wheel, as shown in Fig. 1. The free end of the rope is anchored as indicated at 143 in Fig. 17 and the rope is then wound upon the wheel adjacent the rack 82 as the machine advances. By means of this arrangement the rate of advance of the machine caused by the draft rope 140 will be equal to the normal peripheral speed of the wheel 12 to which the draft rope is attached. 105 110

In Fig. 17 it will be noted that the draft rope 140 is applied to the forward wheel adjacent the working face of the mine and is acting to feed the machine to the coal. It is obvious that a similar draft rope may be attached to the other wheels, as for instance under certain conditions, such as will hereinafter appear, in which it may be desirable to utilize such a rope in connection with one of the wheels on the opposite side of the frame and extending in a direction opposite to that in which the machine is moving. 115 120

In order to facilitate transportation of the machine over tracks in the entries, I provide the wheels 12, 12, with flanges 145 for engaging the track in the usual manner. These flanges are preferably placed adjacent 130

the racks 82 and 85, so as to prevent the cable 140 from being accidentally injured by the drive gears 80 and 84, respectively, when said cable is applied to the periphery.

5 The use and operation of a cutting machine constructed as above described may best be described in connection with the diagrams appearing in Figs. 12 to 17, inclusive.

10 The machine is normally supported by the traction wheels 12, 12, which are power actuated so as to propel the machine from place to place in the mine and are flanged to be guided on the mine tracks, when de-

15 sired. While being moved along the entry or into the room preparatory to cutting, the traction wheels are preferably positioned at their lowest position respective to the main frame, as shown in Fig. 4, so as to pro-

20 vide clearance for the auxiliary supporting pan 16 and the cutter arm 13. Said cutter bar 13 is arranged longitudinally of the machine while being so transported. The machine is capable of being steered when oper-

25 ating on the mine floor, inasmuch as two pairs of traction wheels at the opposite sides of the frame are adapted to be driven at different speeds and controlled independently of each other through the two sets of

30 controlling mechanisms on opposite sides of the frame as hereinbefore described. The machine may thus be guided to the place where it is desired to make a cut.

The machine is particularly adapted for 35 use in the room and pillar system of mining in which the working face at one end of the room is advanced by making successive transverse cuts from one side or "rib" of the room to the other. Referring now to Fig.

40 12, the machine is shown as moved into position at one corner of a room, with the machine parallel to the working face indicated at 150 and with the cutter arm extending from one end thereof into contact with the

45 right hand wall or rib 151. In this position the machine is "sumped", that is to say, it is given its initial cut into the working face. As is the case with the room and pillar sys-

50 tem of mining, it is desirable to extend the lateral walls of the rooms in a substantially straight line and to this end my machine is sumped in the following manner. The machine is lowered on the supporting wheels until the cutter arm 13 is at the desired

55 height from the floor, and the pan 16 is in substantial engagement with the ground. The cutter chain 13^a on the cutter arm 13 is put into operation and the turntable 15 is then rotated so as to swing the cutter arm

60 about its axis to feed the cutter arm to the coal as shown in Fig. 13. Simultaneously, the traction devices are driven slowly to advance the machine bodily to the right and toward the rib 151, so that during the 65 movement of the machine from the position

shown in Fig. 12 to Fig. 13, the outer end of the cutter arm is moved substantially in alignment with the wall 151. While this cutting movement is taking place, it is necessary to lift the traction wheel 12 appearing 70 at the upper right hand corner of the machine in Fig. 12, so as to permit the cutter arm 13 to swing thereunder. Mechanism for raising this wheel independently of the other wheels has been hereinbefore described. 75 While the machine is being supported and propelled on the three wheels remaining in contact with the ground, proper equilibrium is provided by means of the auxiliary support or pan 16 which is normally adapted to 80 have sliding contact with the ground and moves with the cutter arm. This supporting pan 16 is arranged to extend beyond the center of gravity of the machine so that the equilibrium of the latter is maintained at all times. Furthermore, while one of the wheels is raised as described, the cutter arm is already partially under the coal, and further stability to the machine is provided by reason of the reaction of the cutter arm while 85 it is being fed to the coal during this sumping cut, so that under most conditions, this reaction of the cutter bar is sufficient to stabilize the machine irrespective of the support afforded by the pan 16. 90

In Fig. 14 the sumping cut is shown as completed and the machine body has been moved to the right into close proximity with the right wall 151. The cutter arm extends almost at right angles with the longitudinal axis of the machine. From this position the cutter arm may be further rotated into a substantially right angled position with respect to the machine as shown in Fig. 15. The raised wheel 12 may then 100 be lowered into its normal supporting engagement with the ground. Thereafter the entire machine is propelled along the wall to cut a continuous kerf, as indicated in Fig. 15, with the cutter arm locked against pivotal movement by reason of the "self-locking" worm gear drive associated with the turntable, as hereinbefore described. 105

During the transverse cutting movement illustrated in Fig. 15, there is an enormous 115 pressure on the cutter arm as it is being fed to the coal, which tends to twist the machine out of parallelism with the working face. That is to say, the outer side of the machine which is farthest away from the working face has a tendency to advance faster than the inner side. In order to overcome this tendency, the two traction units at opposite sides of the frame are independently controlled in such a manner as to maintain the 120 machine in the desired angular position with respect to the working face. In order to accomplish this purpose, the traction unit nearer the mine wall is used primarily as the feeding means, that is to say, it is driven at 125 130

the desired feeding speed, while the opposite or outer unit is controlled so as to counteract any tendency to twist the machine. The outer traction unit is therefore utilized to retard the movement of the outer side respective to the inner side. The amount of retardation necessary will obviously vary greatly according to cutting conditions. For this purpose, various methods of controlling the retarding unit may be used, depending upon working conditions. The preferred method of control is to disconnect the outer traction unit from the motor by throwing out clutch 86 associated therewith, and then control the brake band 89 manually by means of the handle 89^b. This brake is operative through the idler or reach gear 83 which drives gears 82 and 84, to retard the forward movement of the two wheels 12, 12, at the outer side of the machine. Another method of controlling the outer or retarding unit is to clutch both units to the motor, and release the brake band 53 of transmission device 44 associated with the outer traction unit more than the similar brake band of the inner unit. In this way the outer unit will be positively driven at a slightly lower speed than the inner unit, and there will be a resulting drag on the outer unit, which tends to retard the latter with respect to the inner or feeding unit. The outer unit may also be reversed to drive in an opposite direction with respect to the feeding unit, if desired, by means of the reversing mechanism described.

Under conditions where sufficient traction for feeding the machine to the coal cannot be secured, a supplemental draft device 140 may be connected with one of the inner traction wheels 12 in the manner hereinbefore set forth in connection with the description of Fig. 17. Under these conditions also, the outer traction unit may be utilized as a retarding device and ordinarily will be sufficient to maintain the desired angular position with respect to the wall, but under extraordinary conditions, a second cable may be used in connection with one of the wheels of the retarding unit and trained in a direction opposite to the feeding cable 140.

As the machine approaches the end of the cut at the left hand side of the room as shown in Fig. 16, the cutter arm and turntable are again actuated and swung at an angle to the machine until the outer end of the cutter arm is substantially in alignment with the left hand wall 152. The finishing cut is then made by lifting the wheel 12 appearing in the upper left hand corner of the machine in Fig. 16 so as to allow the cutter arm to swing thereunder, while the machine is simultaneously moved bodily to the right so that the cutter arm finishes the cut in alignment with the wall 152, as indicated in dotted lines in this figure. The machine is

then withdrawn from the room and moved to the next place to be cut.

So far as the general features of my invention are concerned, it is obvious that the machine might be successfully used for most purposes if constructed to cut at one side only, that is to say, if the cutter arm were limited to swing only from one end to the other through an arc of 180°. In this case, the inner traction unit on the cutting side would manifestly be utilized mainly as a feeding element, and the outer traction unit would be utilized mainly as a retarding element. A machine of this character could be constructed somewhat simpler than the form shown, inasmuch as it would only be necessary to provide elevating mechanism for the traction wheels at the cutting side of the machine, and other duplications of parts on opposite sides might also be eliminated, as for instance, the outer traction unit might consist of one traction wheel instead of two, so that the machine would be supported on three wheels instead of four. There is, however, an important advantage of complete reversibility afforded by the construction illustrated which is capable of cutting on both sides of the machine and provided with duplicate, independently controlled traction units. This reversibility feature may be explained as follows: In making the one cut across the face illustrated in Figs. 12 to 16, the cutter arm swings through an arc of approximately 180°. In the initial position shown in Fig. 12 the cutter arm extends from the end adjacent the motor 11, and in Fig. 16 it extends from the opposite end. Owing to the construction of the machine, by which the cutter arm has a range of 360°, and the traction units on opposite sides of the machine being similar, the initial or sumping cut may be made from either end, so that when one cut is completed, as for instance as shown in Fig. 16, the machine may then be moved to the next cutting place in a reversed position, i. e. turned end-to-end with respect to its position in starting the last cut. Therefore, with the preferred form shown, it is not necessary to return the cutter arm to its initial position for each cut, but the machine may be moved to the next cutting place and be presented to the work with the side which was previously the outer side placed adjacent the working face. In making the next cut, the traction unit which was previously the feeding unit then becomes the retarding unit, and vice versa, and the cutter arm swings through approximately 180° at the other side of the machine. When operated in this manner, the cutter arm moves in a complete circle for every two cuts.

The machine may be used advantageously in various systems of mining, as for instance, the longwall or panel systems or for cutting

entries, inasmuch as it is readily propelled and guided and is capable of cutting either at the end or at the sides thereof.

Among the principal advantageous features of my invention is the provision of a unitary structure, including the cutting element and propelling and guiding mechanism therefor, which may be moved over the mine floor without requiring tracks, such as are necessary with cutting machines of the over-cutting or arcutwall type, or of a track supported truck such as are used for transporting continuous cutting machines of the shortwall type. The machine further recommends itself particularly for use where the coal is to be gathered by a scraper or drag line system, in which it is undesirable to have tracks extending into the mine room or adjacent the working place.

Another novel feature of my invention is the application of a traction unit for use as a retarding device on a laterally movable cutting machine. As far as the broad aspect of this feature is concerned, it is obvious that the power for advancing the machine laterally to feed it to the coal may be applied to the inner side of the machine by any means, such as a traction unit as in Fig. 15, or by the sole means of a flexible draft device, in the manner suggested by the modified form illustrated in Fig. 17. Such a retarding traction device is therefore not limited to a traction-fed cutting machine, but can be applied to other types of machines, as for instance to cable-fed machines of the well known types of continuous cutting or shortwall machines. This traction unit includes a brake or its equivalent for controlling the speed of the retarding traction unit, and also is provided with reversible driving connections with the motor, independent of the feeding means, for positively swinging the outer end of the machine in either direction with respect to the inner or feeding end.

Although I have shown as a preferred construction a single motor having operative connection with the various mechanisms, it is manifest that a plurality of independently controlled motors might be utilized for actuating the various mechanisms, if desired, without departing from the broad features of my novel invention. Other specific features of construction might also be changed in many details without departing from the spirit and scope of my invention. I do not therefore wish to be understood as limiting myself to the specific embodiment of the various novel features presented, excepting in so far as particularly set forth in the following claims.

I claim as my invention:

1. In a mining machine, a motor, a frame having a pair of traction devices spaced longitudinally of one side of said frame and normally in supporting engagement with

the ground, and means for operating the same, a cutting element pivotally connected to said frame intermediate said traction devices to swing in a horizontal plane and means operated by said motor for elevating said traction devices to permit said cutting element to pass thereunder.

2. In a mining machine, a motor, a frame having a pair of traction devices spaced longitudinally at one side of said frame and normally in supporting engagement with the ground, and means for operating the same, a cutting element pivotally connected to said frame intermediate said traction devices to swing in a horizontal plane, means operated by said motor for elevating said traction devices in a vertical plane parallel to the longitudinal axis of said frame to permit said cutting element to pass thereunder, and auxiliary supporting means carried by said cutting element and adapted to support a portion of said frame when either of said traction devices is in elevated position.

3. In a mining machine, a motor, a frame having a pair of traction devices spaced longitudinally of one side of said frame and normally in supporting engagement with the ground, a cutting element pivotally connected to said frame intermediate said traction devices to swing in a horizontal plane, means for elevating and lowering said traction devices to permit said cutting element to pass thereunder and driving connections between said motor and said traction devices permitting the latter to be selectively raised and instantaneously resume their tractive effort when lowered.

4. In a mining machine, a motor, a frame having a pair of traction devices spaced longitudinally at one side of said frame and normally in supporting engagement with the ground, a cutting element pivotally connected to said frame intermediate said traction devices to swing in a horizontal plane, means for raising and lowering said traction devices to permit said cutting element to pass thereunder, driving connections between said motor and said traction devices permitting the latter to be selectively raised and instantaneously resume their tractive effort when lowered, and auxiliary supporting means carried by said cutting element arranged to support a portion of said frame when the other of said traction devices is in elevated position.

5. In a mining machine, a frame, a motor, a pair of traction devices spaced along one side of said frame and normally in supporting engagement with the ground, a cutting element pivotally connected to said frame on a vertical axis within the boundaries of said traction devices, means affording independent vertical movement of said traction

devices to permit said cutting element to pass thereunder, said last named means having operative connection with the motor to return said traction devices, when in raised position, into normal supporting engagement with the ground.

6. In a mining machine, in combination, a frame, a motor, a plurality of supporting members movable vertically with respect to said frame and normally adapted to support the latter, a cutting element pivotally supported on said frame within the boundaries defined by said supporting members and adapted to extend beyond said boundaries, and means driven by said motor for independently operating said cutting element and said supporting means to permit the cutting element to pass thereunder.

7. In a mining machine, in combination, a frame, a plurality of supporting members movable vertically with respect to said frame and normally adapted to support the latter, a cutting element pivotally supported on said frame within the boundaries defined by said supporting members and adapted to extend beyond said boundaries, means for independently operating said supporting means to permit the cutting element to pass thereunder, and an auxiliary support within the boundaries defined by said supporting means as aforesaid, but extending beyond the center of gravity of said machine in a direction toward one of said supporting means when the latter is out of supporting engagement with the ground.

8. In a mining machine, in combination, a frame, a plurality of supporting members movable vertically with respect to said frame and normally adapted to support the latter, a cutting element pivotally supported on said frame within the boundaries defined by said supporting members and adapted to extend beyond said boundaries, means for independently operating said supporting means to permit the cutting element to pass thereunder, and an auxiliary support within the boundaries defined by said supporting means as aforesaid, but extending beyond the center of gravity of said machine in a direction toward one of said supporting means when the latter is out of supporting engagement with the ground, said auxiliary support being movable with said cutting mechanism.

9. In a mining machine, a frame, a motor, a pair of longitudinally spaced traction devices normally in supporting engagement with the ground, and having operative connection with said motor, a cutting element pivotally connected to said frame intermediate said traction devices, means affording vertical movement of one or more of said traction devices to permit said cutting element to pass thereunder, said last named means having operative connection with the

motor to return said traction device, when in raised position, into normal supporting engagement with the ground.

10. In a mining machine, the combination of a frame, a motor, a traction device having operative connection with said motor and normally adapted to engage the ground, a cutting element pivotally mounted on said frame and extending beyond said traction device, means operatively connecting said motor with said cutting element, power devices driven by said motor affording vertical movement of said traction device relative to said cutting element to permit the latter to swing on opposite sides of said traction device, means associated with said last named power devices adapted to return said traction device into normal supporting engagement with the ground, and an auxiliary support adapted to engage the ground while said traction device is in elevated position, said auxiliary support being movable with said cutting element.

11. In a mining machine adapted for room and pillar mining, the combination of a frame, a kerf cutting element pivotally mounted centrally of said frame and adapted to laterally project from the inner side of said frame, a pair of power driven traction units operable for feeding said machine along the face of the coal and disposed at the inner side of said frame, and on advance and receding sides of said cutting element when the latter is in laterally extending position, and an independently controlled traction device at the outer side of said frame operable for equalizing the reaction on the cutter bar during its feeding movement and thereby maintain the machine at the desired angular relation to the mine face.

12. In a mining machine adapted for room and pillar mining, the combination of a frame, a kerf cutting element pivotally mounted centrally of said frame and projecting at the inner side of said frame, a pair of power driven traction units operable for feeding said machine along the face of the coal and disposed at the inner side of said frame, and on the advance and receding sides of said cutting element when the latter is in laterally extending position, and an independently controlled differentially operable traction device at the outer side of said frame operable for equalizing the reaction on the cutter bar during its feeding movement and thereby maintain the machine at the desired angular relation to the mine floor.

13. In a mining machine adapted for room and pillar mining, the combination of a frame, a kerf cutting element pivotally mounted centrally of said frame and projecting at the inner side of said frame, a pair of power driven traction units operable for feeding said machine along the face of the coal and disposed at the inner side of

- 5 said frame, and on the advancing and receding sides of said cutting element when the latter is in laterally extending position, and an independently controlled traction device at the outer side of said frame operable for equalizing the reaction on the cutter bar during its feeding movement and thereby maintain the machine at the desired angular relation to the mine face, and a friction 10 brake for controlling said last named traction device.
14. In a mining machine, a frame, a cutting element extending laterally from said frame, a traction device for feeding the machine bodily along the face of the coal to cut a kerf, and supplemental feeding means comprising a draft cable wound on the periphery of said traction device and adapted to be anchored to a fixed support in advance of the machine.
15. In a mining machine, a frame, a cutting element extending laterally from said frame, a traction device adjacent the inner or cutting side thereof for feeding the machine bodily along the face of the coal to cut a kerf, and supplemental feeding means comprising a draft cable wound on the periphery of said traction device and adapted to be anchored to a fixed support in advance of the machine.
16. In a mining machine, a frame, a cutting element extending laterally from intermediate the ends of said frame, a traction device adjacent the inner or cutting side thereof for feeding the machine bodily along the face of the coal to cut a kerf, supplemental feeding means comprising a draft cable adapted to be anchored to a fixed support in advance of the machine and wound on the periphery of said traction device, and means offset from said feeding means for retarding the movement of the outer end of the machine.
17. In a mining machine, a frame, a cutting element extending laterally from intermediate the ends of said frame, a traction device adjacent the inner or cutting side thereof for feeding the machine bodily along the face of the coal to cut a kerf, supplemental feeding means comprising a draft cable adapted to be anchored to a fixed support in advance of the machine and wound on the periphery of said traction device, a power-driven traction device offset from said feeding means, and means independent of said feeding means for controlling said last named traction device.
18. In a mining machine, a frame, a cutting element extending laterally from intermediate the ends of said frame, a traction device adjacent the inner or cutting side thereof for feeding the machine bodily along the face of the coal to cut a kerf, supplemental feeding means comprising a draft cable adapted to be anchored to a fixed support in advance of the machine and wound on the periphery of said traction device, a power-driven traction device offset from said feeding means, and means for reversing said traction device respective to said feeding means, whereby they may be driven either in the same or opposite directions.
19. In a mining machine, a frame, a cutting element extending laterally from intermediate the ends of said frame, a traction device adjacent the inner or cutting side thereof for feeding the machine bodily along the face of the coal to cut a kerf, supplemental feeding means comprising a draft cable adapted to be anchored to a fixed support in advance of the machine and wound on the periphery of said traction device, a traction device offset from said feeding means and manually operated retarding means for controlling the movement of said last named traction device independent of said feeding means.
20. In a mining machine, a frame, a cutting element extending laterally from intermediate the ends of said frame, a traction device adjacent the inner or cutting side thereof for feeding the machine bodily along the face of the coal to cut a kerf, supplemental feeding means comprising a draft cable adapted to be anchored to a fixed support in advance of the machine and wound on the periphery of said traction device, a traction device offset from said feeding means, and a brake for controlling the movement of said last named traction device independent of said feeding means.
21. In a mining machine, a frame, a cutting element extending laterally from intermediate the ends of said frame, a traction device adjacent the inner or cutting side thereof for feeding the machine bodily along the face of the coal to cut a kerf, supplemental feeding means comprising a draft cable adapted to be anchored to a fixed support in advance of the machine and wound on the periphery of said traction device, a power-driven traction device offset from said feeding means, and means for varying the driving speed of said last named traction device independent of the feeding means.
22. In a mining machine, a frame, a cutting element extending laterally from intermediate the ends of said frame, a traction device adjacent the inner or cutting side thereof for feeding the machine bodily along the face of the coal to cut a kerf, supplemental feeding means comprising a draft cable adapted to be anchored to a fixed support in advance of the machine and wound on the periphery of said traction device, a power-driven traction device offset from said feeding means, and means for reversing said traction device respective to said feeding means, whereby they may be driven either in the same or opposite directions.
23. In a mining machine, a frame, a mo-

- tor, a plurality of traction wheels adjustable vertically in several supporting positions respective to said frame and having continuous operative connection with said motor in the several permissible positions thereof, a horizontally disposed turntable rotatably mounted on said frame within said wheels, a horizontally disposed cutter frame beneath said turntable, an auxiliary supporting pan beneath the inner end of said cutter arm, and normally maintained out of supporting engagement with the ground by said traction wheels, said turntable, cutter arm and pan being rigidly connected together.
24. In a mining machine, a frame, a motor, a plurality of traction wheels adjustable vertically in several supporting positions respective to said frame, and having continuous operative connection with said motor in the several permissible positions, a horizontally disposed turntable rotatably mounted on said frame within said wheels, a horizontally disposed cutter arm beneath said turntable, a sprocket shaft extending concentrically through said turntable, a chain sprocket on said shaft adjacent the inner end of said cutter arm, a cutter chain and an auxiliary supporting pan beneath the inner end of said cutter arm and said sprocket and normally maintained out of supporting engagement with the ground by said traction wheels, said turntable, cutter arm and pan being rigidly connected together.
25. In a mining machine, a frame, a motor, a plurality of traction wheels adjustable vertically in several supporting positions respective to said frame, a horizontally disposed turntable rotatably mounted on said frame within said supports, a horizontally disposed cutter arm beneath said turntable, a sprocket shaft extending concentrically through said turntable, a chain sprocket on said shaft adjacent the inner end of said cutter arm, a cutter chain, a pan beneath the inner end of said cutter arm and said sprocket, said turntable, cutter arm and pan being rigidly connected together, means for actuating said chain, and means controlled independently of said last named means for swinging said turntable angularly with respect to the frame to feed the cutter arm to the coal.
26. In a mining machine, a frame, a motor, a plurality of traction wheels adjustable vertically in several supporting positions respective to said frame, a horizontally disposed turntable rotatably mounted on said frame within said supports, a horizontally disposed cutter arm beneath said turntable, a sprocket shaft extending concentrically through said turntable, a chain sprocket on said shaft adjacent the inner end of said cutter arm, a cutter chain, a pan beneath the inner end of said cutter arm and said sprocket, said turntable, cutter arm and

pan being rigidly connected together, gearing operatively connected with said motor for actuating said cutter chain, and other gearing operatively connected with said motor for swinging said turntable angularly at a lower speed to feed the cutter arm to the coal.

27. In a mining machine, a frame, a horizontally disposed cutter arm movable into various positions to cut at one side and at opposite ends of said frame, a pair of longitudinally spaced rotatable traction devices capable of being driven in either direction adjacent the inner or cutting side of said frame adapted to feed the cutter arm to the coal, said traction devices being movable vertically with respect to said cutter arm to permit the latter to pass thereunder, and an independently controlled traction unit capable of being driven in either direction offset and spaced laterally from said pair of traction devices.

28. In a mining machine, a frame, a horizontally disposed cutter arm movable into various positions to cut at one side and at opposite ends of said frame, a pair of longitudinally spaced rotatable traction devices capable of being driven in either direction adjacent the inner or cutting side of said frame adapted to feed the cutter arm to the coal, said traction devices being movable vertically with respect to said cutter arm to permit the latter to pass thereunder, a traction unit capable of being driven in either direction offset and spaced laterally from said pair of traction devices, and controlling means associated with said traction unit for retarding the outer end of the machine while it is being fed to the coal.

29. In a mining machine, a frame, a horizontally disposed cutter arm movable into various positions to cut at one side and at opposite ends of said frame, a pair of longitudinally spaced rotatable traction devices capable of being driven in either direction adjacent the inner or cutting side of said frame adapted to feed the cutter arm to the coal, said traction devices being movable vertically with respect to said cutter arm to permit the latter to pass thereunder, a traction unit capable of being driven in either direction offset and spaced laterally from said pair of traction devices, and manually controlled brake mechanism associated with said traction unit for retarding the outer end of the machine while it is being fed to the coal.

30. In a mining machine, a frame, a horizontally disposed cutter arm movable into various positions to cut at one side and at opposite ends of said frame, a pair of longitudinally spaced rotatable traction devices capable of being driven in either direction adjacent the inner or cutting side of said frame adapted to feed the cutter arm to the

coal, said traction devices being movable vertically with respect to said cutter arm to permit the latter to pass thereunder, a traction unit capable of being driven in either 5 direction offset and spaced laterally from said pair of traction devices, and driving means for said traction unit controlled independently of said feeding traction devices.

31. In a mining machine, a frame, a horizontally disposed cutter arm movable into various positions to cut at one side and at opposite ends of said frame, a pair of longitudinally spaced rotatable traction devices adjacent the inner or cutting side of said 15 frame adapted to feed the cutter arm to the coal, said traction devices being movable vertically with respect to said cutter arm to permit the latter to pass thereunder, a traction unit offset and spaced laterally from 20 said pair of traction devices, and reversible driving means for said traction unit controlled independently of said feeding traction devices.

32. In a mining machine, a frame, a horizontally disposed cutter arm movable into various positions to cut at one side and at opposite ends of said frame, a pair of longitudinally spaced rotatable traction devices adjacent the inner or cutting side of said 30 frame adapted to feed the cutter arm to the coal, said traction devices being movable vertically with respect to said cutter arm to permit the latter to pass thereunder, a traction unit capable of being driven in either 35 direction offset and spaced laterally from said pair of traction devices, and differential driving means for said traction unit controlled independently of said feeding traction devices.

33. In a mining machine, a frame, a horizontally disposed cutter arm movable into various positions to cut at one side and at opposite ends of said frame, a pair of longitudinally spaced rotatable traction devices 45 adjacent the inner or cutting side of said frame adapted to feed the cutter arm to the coal, said traction devices being movable vertically with respect to said cutter arm to permit the latter to pass thereunder, a traction 50 unit offset and spaced laterally from said pair of traction devices, and an auxiliary support movable with said cutter arm and adapted to maintain the equilibrium of the machine while one of said traction devices is in elevated position.

34. In a mining machine, a frame, a horizontally disposed cutter arm movable into various positions to cut at one side and at opposite ends of said frame, a pair of longitudinally spaced rotatable traction devices 60 adjacent the inner or cutting side of said frame adapted to feed the cutter arm to the coal, said traction devices being movable vertically with respect to said cutter arm to 65 permit the latter to pass thereunder, a trac-

tion unit offset and spaced laterally from said pair of traction devices, and a shoe movable with said cutter arm and adapted to have sliding engagement with the ground to maintain the equilibrium of the machine 70 while one of said traction devices is in elevated position.

35. In a mining machine, a frame, a motor, a horizontally disposed cutter arm pivotally mounted on said frame to swing in a 75 complete circle and cut at both ends and sides of said frame, a plurality of traction devices for supporting and propelling said machine, each of said traction devices being adjustable vertically in several positions 80 with respect to said cutter arm to permit the latter to pass thereunder, and driving connections between said motor and said traction devices permitting the latter to be selectively raised and instantaneously resume 85 their tractive effort when lowered.

36. In a mining machine adapted for use in room and pillar mining, a frame, a horizontally disposed cutter arm pivotally mounted on said frame adapted to extend a 90 substantially equal distance in advance of both ends thereof, means for simultaneously feeding said cutter arm angularly to the coal, and means for feeding and guiding the machine bodily along the working face, 95 said last named means being reversible to withdraw the machine from the face after the cutter arm has been moved from one end to the other through an angle of approximately 180 degrees in making a cut at one side of the machine, and to feed and guide the machine in the opposite direction for the next cut, with the cutter arm at the other side of the machine.

37. In a mining machine adapted for use in room and pillar mining, a frame, a horizontally disposed cutter arm pivotally mounted on said frame adapted to extend in cutting position on all sides thereof, means for feeding said cutter arm angularly to the 105 coal, and a plurality of laterally spaced, independently controlled traction devices for feeding and guiding the machine bodily along the working face, said traction devices being reversible to withdraw the machine 110 from the face after the cutter arm has been moved from one end to the other through an angle of approximately 180 degrees in making a cut at one side of the machine, and to feed and guide the machine in the opposite direction for the next cut with the cutter arm 115 at the other side of the machine, and means for moving each of said traction devices vertically to permit said cutter arm to pass thereunder.

38. In a mining machine, a frame, a motor, a horizontally disposed cutter bar pivotally mounted intermediate the ends of said frame to extend from both ends and at intermediate points about said frame, a pair 120

of rotatable traction devices adjacent the cutting side of said frame and having their axes spaced longitudinally of the pivotal point of said cutter arm whereby the latter, when positioned transversely of the frame, extends laterally between within the vertical limits of said traction devices, and reversible connections between said motor and said traction devices for driving the latter in either direction.

39. In a mining machine, a frame, a motor, a horizontally disposed cutter bar pivotally mounted centrally of said frame to extend from both ends thereof and to cut at intermediate points about said frame, four rotatable traction devices at the corners of said frame, each pair of said traction devices having their axes spaced longitudinally of the pivotal point of said cutter arm on opposite sides thereof whereby the latter extends between within the vertical limits of each adjacent pair of traction devices when positioned at the sides or ends of said frame, and reversible connections between said motor and said traction devices for driving the latter in either direction.

40. In a mining machine, a frame, four vertically movable traction devices at opposite corners of said frame, a motor adjacent one end of said frame between two of said traction devices, a turntable rotatably mounted centrally of said frame and extending beneath said motor, a cutting element carried by said turntable, speed reducing gearing at the end of the machine opposite said motor, said speed reducing mechanism having operative connection with said traction devices.

41. In a mining machine, a frame, four vertically movable traction devices at opposite corners of said frame, a motor adjacent one end of said frame between two of said traction devices, a turntable rotatably mounted centrally of said frame and extending beneath said motor, a cutting element carried by said turntable, speed reducing gearing at the end of the machine opposite said motor, said speed reducing mechanism having operative connection with said traction wheels, and having an independently controlled connection with said turntable to rotate the latter.

42. In a mining machine, a frame, four vertically movable traction devices at opposite corners of said frame, a motor adjacent one end of said frame between two of said traction devices, a turntable rotatably mounted centrally of said frame and extending beneath said motor, a cutting element carried by said turntable, provided with a cutter chain, a drive shaft and sprocket for said chain mounted concentrically of said turntable and operatively connected with said motor, speed reducing gearing at the end of the machine opposite said motor, said

speed reducing mechanism having operative connection with said traction wheels, and having an independently controlled connection with said turntable to rotate the latter.

43. In a mining machine, a frame, a cutting element extending laterally from said frame, a traction wheel for feeding the machine bodily along the face of the coal to cut a kerf, and supplemental feeding means comprising a detachable draft cable wound on the periphery of said traction wheel and adapted to be anchored to a fixed support in advance of the machine.

44. In a mining machine, a frame provided with suitable cutting mechanism for cutting a kerf, a traction wheel for feeding the machine bodily along the face of the coal, a motor, and a spur gear mounted in said frame and meshed with a rack formed in the outer periphery of said traction wheel, said gear having operative connection with the motor, and vertically adjustable supporting means for said traction wheels pivotally connected to said frame concentric with said gear.

45. In a mining machine, a frame provided with suitable cutting mechanism for cutting a kerf, a traction wheel for feeding the machine bodily along the face of the coal, a motor, a spur gear mounted in said frame and meshed with a rack formed in the outer periphery of said traction wheel, said gearing having operative connection with the motor, and supplemental feeding means comprising a draft cable adapted to be anchored to a fixed support in advance of the machine and wound on the outer periphery of said traction wheel adjacent said rack.

46. In a mining machine, a frame provided with suitable cutting mechanism for cutting a kerf, a traction wheel for feeding the machine bodily along the face of the coal, a driving gear mounted in said frame, a rack formed in the periphery of said traction wheel and meshed with said gear, a series of projections also formed about said periphery, and supplemental feeding means comprising a draft cable wound about said periphery adjacent said rack and said series of projections and adapted to be anchored to a fixed support in advance of the machine.

47. In a mining machine, a frame, a plurality of traction wheels, means for controlling said traction wheels to guide the mining machine during its cutting operation, and a draft cable detachably connected to and wound about the periphery of one of said traction wheels and adapted to afford additional draft to the latter.

48. In a mining machine, a frame, a cutting element pivotally mounted beneath said frame to cut a substantially horizontal kerf adjacent the mine floor, a plurality of power actuated traction wheels and an intermediate auxiliary support adapted to engage the

5 ground during a portion of the cutting operation, and means for raising and lowering said frame with respect to said wheels to permit increased clearance of said cutting element and support with respect to the mine floor while the machine is being transported from place to place.

10 49. In a mining machine, a frame, a cutting element pivotally mounted beneath said frame to cut a substantially horizontal kerf adjacent the mine floor, a pan fixed beneath the inner end of said cutting element and adapted to provide an auxiliary support for said frame during a portion of the cutting 15 operation, a plurality of power actuated traction wheels adapted to support said machine, and means for raising and lowering said frame with respect to said wheels to permit increased clearance of said cutting element and said pan with respect to the 20 mine floor while the machine is being transported from place to place on said traction wheels.

25 50. In a mining machine, a motor, a frame, a cutting element pivotally mounted beneath said frame to swing in a horizontal plane, a plurality of supporting arms pivotally mounted on axes arranged transversely of said frame to swing on a vertical 30 plane, traction wheels journaled in said arms, and means for pivotally swinging said arms to selectively move said traction wheels vertically above the level of said cutting element, and power connections between said motor and said traction wheels in 35 all permissible positions thereof.

40 51. In a mining machine, a frame, a cutting element pivotally mounted beneath said frame to swing in a horizontal plane, a plurality of supporting arms pivotally mounted on said frame to swing in a vertical plane, traction wheels journaled in said arms, and motor driven means for pivotally swinging said arms to move said traction wheels vertically above the level of said cutting element.

45 52. In a mining machine, a frame, a cutting element pivotally mounted beneath said frame to swing in a horizontal plane, a plurality of supporting arms pivotally mounted on said frame to swing in a vertical plane, traction wheels journaled in said arms, means for pivotally swinging said arms to move said traction wheels vertically above the level of said cutting element, and motor driven gears for driving said traction wheels mounted to rotate concentrically with said pivoted arms, and having operative connection with said traction wheels in all positions 50 of the latter.

55 53. In a mining machine, a frame, a cutting element pivotally mounted beneath said frame to swing in a horizontal plane, a pair of traction units on opposite sides of said 60 frame, each comprising a pair of arms piv-

otally mounted on said frame to swing in a vertical plane, a traction wheel journaled on each of said arms, power actuated mechanism for swinging said arms to move its respective traction wheel vertically above the level of said cutting element, and other power actuated mechanism for driving said traction unit including a pair of spur gears each rotatably mounted concentric with one of said arms and having operative connection with its respective wheel, both of said spur gears being connected to drive the wheels at uniform speed and in the same direction.

54. In a mining machine, a frame, a cutting element pivotally mounted on said frame to swing in a horizontal plane, a pair of traction units on opposite sides of said frame, each comprising a pair of arms pivotally mounted on said frame to swing in a vertical plane, a traction wheel journaled on each of said arms, power actuated mechanism for swinging each of said arms independently of the others to move its respective traction wheel vertically respective to said frame, and other power actuated mechanism for driving said traction unit including a pair of gears each rotatably mounted concentric with one of said arms, and having operative connection with its respective wheel, both of said gears being connected to drive the wheels at uniform speed and in the same direction.

55. In a mining machine, a frame, a cutting element pivotally mounted on said frame to swing in a horizontal plane, a pair of traction units on opposite sides of said frame, each comprising a pair of longitudinally disposed arms pivotally mounted on said frame to swing in a vertical plane, a traction wheel journaled on each of said arms, power actuated mechanism for swinging each of said arms independently of others to move its respective traction wheel vertically respective to said frame, and other power actuated mechanism for driving said traction unit controlled independently of the other unit, and including a pair of gears each rotatably mounted concentric with one of said arms, and having operative connection with its respective wheel, both of said gears being connected to drive the wheels at uniform speed and in the same direction.

56. In a mining machine, the combination of a frame, a cutting element pivotally mounted beneath said frame, a plurality of power actuated traction devices adapted normally to propel the machine along the mine floor, means for raising and lowering said traction devices vertically relative to said frame an auxiliary, centrally disposed support carried by said frame, and means on said traction devices adapted to engage a track.

57. In a mining machine adapted for room

and pillar mining, a frame, a motor, a kerf cutting element pivotally mounted centrally of said frame to swing in a horizontal plane, a plurality of traction devices adapted to support the machine and feed the cutting element to the coal by tractive effort while the machine is being moved bodily along the working face, and power connections between said motor and said traction devices including change-speed transmission devices affording selective movement of said machine at a predetermined cutting speed or at a higher moving speed for transporting the machine from place to place in the mine.

58. In a mining machine adapted for room and pillar mining, a frame, a motor, a kerf cutting element pivotally mounted centrally of said frame to swing in horizontal plane, a plurality of traction devices adapt-

ed to support the machine and feed the cutting element to the coal by tractive effort while the machine is being moved bodily along the working face, power connections between said motor and said traction devices including change-speed transmission devices affording selective movement of said machine at a predetermined cutting speed or at a higher moving speed for transporting the machine from place to place in the mine, and means driven by said motor for selectively raising said traction devices out of supporting engagement with the ground to permit said cutting element to swing thereunder.

Signed at Chicago, in the county of Cook and State of Illinois, this second day of June, 1922.

CHARLES E. DAVIS.
